UNITED STATES PATENT OFFICE.

ARTHUR LEE LIGON, OF PECOS, TEXAS.

DETACHABLE HANDLE FOR TOOLS.

1,152,327.

Specification of Letters Patent. Patented Aug. 31, 1915.

Application filed December 31, 1914. Serial No. 879,867.

To all whom it may concern:

Be it known that I, ARTHUR LEE LIGON, a citizen of the United States of America, residing at Pecos, in the county of Reeves 5 and State of Texas, have invented certain new and useful Improvements in Detachable Handles for Tools, of which the following is a specification, reference being had therein to the accompanying drawing.

10 This invention relates to a detachable handle for tools and has for its object the production of a simple and efficient mechanism whereby several different tools may be attached to the handle within a minimum 15 amount of time.

Another object of this invention is the production of a simple and efficient handle so constructed as to prevent the handle from being accidentally detached or released from 20 the tool which it carries.

With these and other objects in view this invention consists of certain novel combinations, constructions, and arrangements of parts as will be hereinafter fully described 25 and claimed.

In the accompanying drawings:—Figure 1 is a plan view of a portion of the handle partly in section. Fig. 2 is a side elevation of the tool gripping portion of the handle 30 showing the forward end thereof in engagement with a tool head. Fig. 3 is a plan view of the locking mechanism for the handle, the handle being partly broken away to show the securing lug or tongue. Fig. 4 is a 35 sectional view of an embodiment of the present invention showing a slightly modified form of the locking mechanism and tool engaging portion of the handle. Fig. 5 is a side elevation of the forward end of the 40 handle mechanism shown in Fig. 4.

It should be understood that the present device has special reference to a handle which is adapted to engage or support any number of different kinds or shaped tools, 45 and that these tools may be readily placed upon or disengaged from the handle when so desired. It is not desired to limit the present application to any special form or design of tool which may be carried by the 50 handle, and it is desired to be pointed out that any shape or desired form of tool may be mounted upon the handle without departing from the spirit of the invention.

By referring to the drawings it will be 55 seen that 1 designates the shank of the handle which is provided with a rearwardly ex-

tending metallic web 2. A plurality of wooden or other filler blocks 3 are placed upon the web 2 and are firmly held thereon by means of suitable rivets 4. The shank 1 60 is provided with a rigid tool engaging jaw 5 and a movable tool engaging jaw 6. The jaw 5 is provided with a plurality of pockets or notches 7 for the purpose of facilitating the securing of a tool 8 thereto in any 65 desired or suitable manner. The movable or swinging jaw 6, as well as the stationary jaw 5 are formed substantially semi-circular in shape so as to produce a circular pocket for gripping the tool 8. The pivoted jaw 6 is pivotally secured to the stationary jaw 7 by means of a pivot pin 9. The jaw 6 is provided with a rearwardly extending web 10, which web is provided with an integral inwardly extending housing 11. 70 The housing 11 is provided with an aperture 12 formed at one end thereof for the purpose of receiving the forward end 13 of the spring pressed locking bolt 14.

The shank 10 is provided at its rear end 80 with a hinged locking tongue 15, which tongue 15 is provided with a guiding lug 16 upon its inner face for the purpose of receiving the spring pressed locking bolt 14. As is illustrated in Fig. 1 in dotted lines, 85 the pivot jaw or shank 10 may be swung to the position shown in dotted lines for the purpose of removing the tool 8 from engagement with the handle. The locking bolt 14 carries a coil spring 17 which bears 90 against the inwardly extending lug 16, and this bolt 14 also carries an operating knob 18 which is fixedly secured to the bolt and against which one end of the coil spring 17 95 presses. It should be understood that the locking bolt 14 is adapted to fit in the aperture 12 of the shank 10 when in its normal position so as to allow the shank 10 to be held in a locked position relative to the shank 1. The knob 18 carries an inwardly 100 projecting finger 19, which is fixedly secured to the bolt 14, and this finger 19 works in a longitudinally extending slot 20 formed in the tongue 15. The rear end of the tongue 15 is provided with a rearwardly projecting 105 narrow lip 21, which lip is adapted to overhang the body portion of the shank 1 as indicated at 22 for the purpose of holding the tongue 15 and shank 10 against outward swinging movement when the bolt 14 is in 110 its normal position as illustrated in Fig. 1.

Particular attention is invited to Fig. 3

wherein the particular construction of the tongue 15 is specifically illustrated. The narrow lip 21 is shown in Fig. 3 by having a portion of the shank 1 broken away to indicate the manner in which the tongue 15 is formed with respect to the lip 21.

In Figs. 4 and 5 there is shown an embodiment of the invention wherein the shank 23 is provided with a stationary jaw 24 to which 10 jaw is hingedly secured the movable jaw 25 by means of the hinge 26 at the outer end thereof. The movable jaw 25 is provided with a shank 27 having an inwardly projecting housing 28, which housing carries a 15 spring pressed plunger 29 similar to the structure illustrated and described with respect to Fig. 1. The plunger 29 works through a plurality of apertured lugs 30 and carries a pin 31 having an operating knob 20 32 formed thereon. The pin 31 works in a longitudinally extending slot 33 formed in the tongue 34 which is similarly constructed to the tongue 15 illustrated in Fig. 1. The spring pressed plunger 29 works through 25 an aperture 34' formed in the inwardly extending housing 28 for the purpose of holding the tongue 34 in a locked position with respect to the shank 27. In Fig. 5 there is 30 illustrated a side elevation of the construction which is specifically illustrated in detail in Fig. 4.

Having thus described the invention what is claimed as new, is:—

1. A device of the class described comprising a stationary shank and a pivotally mounted shank, tool gripping means carried by said shanks, said pivoted shank provided with an inwardly extending casing adapted to fit in said stationary shank, said 35 40 pivoted shank provided with a hinged tongue secured thereto, a projection carried by said tongue and adapted to engage said

stationary shank for holding said pivoted shank in a set position with respect to said stationary shank, and locking means carried 45 by said tongue and engaging said pivoted shank for holding said tongue against outward swinging movement with respect to said stationary tongue.

2. A device of the class described comprising a stationary shank and a pivotally mounted shank, tool gripping means carried by said shanks, said pivotally mounted shank provided with a hinged tongue, said hinged tongue provided with a projecting 50 55 rib adapted to engage a portion of said stationary shank for holding said pivoted shank in a set position with respect to said stationary shank, and locking means carried by said tongue and engaging said pivoted shank for holding said tongue against swinging movement with respect to said pivoted shank.

3. A device of the class described comprising a stationary shank, a pivoted shank 65 secured thereto, said pivoted shank provided with an inwardly extending integral casing, a pivoted tongue secured to said casing, a lip carried by said pivoted tongue, a spring pressed plunger carried by said pivoted tongue, a knob working in said plunger 70 for facilitating the throwing of the same to an inoperative position, and said inwardly extending casing provided with a pocket for receiving said plunger whereby said plunger may hold said tongue in a locked position with respect to said pivoted shank.

In testimony whereof I hereunto affix my signature in presence of two witnesses.

ARTHUR LEE LIGON.
